C. S. NONNEMACHER.
STRAP FASTENER.
APPLICATION FILED SEPT. 10, 1921,

Patented July 4, 1922.

UNITED STATES PATENT OFFICE.

CLYDE S. NONNEMACHER, OF WENONAH, NEW JERSEY.

STRAP FASTENER.

1,421,813.

Specification of Letters Patent. Patented July 4, 1922.

Application filed September 10, 1921. Serial No. 499,739.

To all whom it may concern:

Be it known that I, CLYDE S. NONNEMACHER, a citizen of the United States, residing at Wenonah, in the county of Gloucester and State of New Jersey, have invented certain new and useful Improvements in a Strap Fastener, of which the following is a specification.

This invention relates to improvements in strap fastener devices and has for its object to render the same more simple in operation, to reduce the cost of production of such devices and to secure a more certain binding effect upon the article to be held. To these and other ends the invention consists in the novel features of construction and combinations of elements hereinafter described.

The prescribed form of the invention is illustrated in the accompanying drawings, in which:

Figure 1 is a perspective view of the strap fastener device shown as encircling several books which are intended to be held together.

Figure 2 is an enlarged front view of that portion of the device comprising the metal member and the strap projection.

Figure 3 is a sectional plan view on line 3-3 of Figure 2.

Figure 4 represents a modification of the slotted metal member shown in Figures 1, 2 and 3 in which metal of a circular cross section is employed.

Figure 5 is a modification of the slotted metal member shown in Figures 1, 2 and 3 in which the member is formed of one continuous piece of metal.

In the device illustrated in Figure 1, the object to be held is represented by several books 1 and encircling these books is the strap 2, composed for the purposes of my description of canvas webbing of sufficient thickness and width to withstand the weight of the objects when suspended from the strap. The respective ends of the straps 3 and 4 are formed in a manner to be presently described and the folding of the material at the ends represents one of the novel features of my invention. In order to more clearly understand the manner of folding the material, reference should be made to Figure 2, in which a portion of the strap 2 is illustrated as folded once upon itself as shown at 5. A second fold of the material is then made in

the same manner and is represented in the figure as 6. There then remains a portion of 55 the strap comprising the end 3 and in order to secure this end it is formed as shown, by tucking or placing it between the first mentioned fold 5, and then stitching the three 60 thicknesses or plies of the material as shown at 7 and 8. Any other suitable means of securing or fastening together the plies may be employed as a substitute for the stitching provided the relation between the strap and metal member is not changed. This novel 65 means of folding the end portion of the strap causes a lateral projection 9 to be formed, the use of which will be more fully described.

When the strap fastener device is being formed, the ends 3 and 4 are so folded that 70 when the respective ends are stitched at 8, the lateral projections 9 and 9' will be facing towards each other and will also be on the same surface of the strap.

The slotted metal member 10 is preferably 75 made as shown in Figure 3 and is of sufficient thickness to withstand the strain to which it may be subjected.

This slotted member may be made of flattened material or of rounded material as 80 shown in the modification 11 in Figure 4. Figure 5 also shows a modification of this metal member formed of one continuous piece. In forming the member as shown in Figure 3, the slot is formed by bending the 85 metal until the slot is of a sufficient width to allow not more than twice the thickness of the strap to pass therethrough. This width is represented by the cross-hatched portion 15 which shows twice the thickness of the 90 strap 2. The length of the slot is made sufficiently large so that the full width of strap 2 may pass through easily. The ends 13 and 14 of the metal member are bent back upon themselves substantially as shown. 95

In adapting the device to encircle an article, a looped portion of the strap is passed through the slot in the metal member as shown in Figure 1, and secured to the article. Either one of the ends of the strap, in this 100 case end 4, is pulled to tighten the device, and as the strap tightens about the article, the lateral projection 9 is caused to engage the metal member 10 and bind against the adjacent face of the opposite end of the strap, 105 thereby causing the strap 2 to encircle the

article tightly and give a more certain binding effect.

Changes in size, shape and the materials of the parts may be made without departing 5 from the scope of the invention.

I claim:—

1. In a strap fastener device, the combination of a metal member having a slot therethrough, a strap having a looped portion extending through said slot and adapted to encircle an article to be held, said slot being of a width adapted to receive not more than twice the thickness of said strap, one of the ends of said strap having a lateral projection 10 formed of a thickened portion of the strap material and on the face thereof next adjacent the opposite end portion, said projection extending toward and having the tip end thereof frictionally engaging the adjacent opposite face of said opposite end portion, and being adapted to be drawn 15 toward said slot and between the two strap ends projecting therethrough.

2. In a strap fastener device, the combination of a retaining member having a slot therethrough, two strap portions extending through said slot, one end of said two strap portions being adapted to engage an article to be held, one of the opposite ends of said 20 two strap portions having a lateral projection formed of the material of the strap and on that face thereof next adjacent the other of said two strap portions, which latter of said strap portions extends to be pulled to 25 tighten the device, said lateral projection extending toward and having the tip end thereof frictionally engaging the adjacent opposite face and being adapted to be drawn toward said slot and between the two strap 30 portions extending through said slot.

3. In a strap fastener device of the character described, a strap having the end thereof folded twice back upon itself for a portion of its length and stitched immediately adjacent the fold, said folded portion formed by the stitching comprising a three 35 ply portion projecting laterally and being adapted to engage the surface of the opposite end and the extreme free end being straightened substantially into line with the main portion of the strap, and a slotted retaining member embracing said strap and engaging said folded portion.

4. In a strap fastener device of the character described, a strap having the end 55 thereof folded back upon itself for a portion of its length and fastened together immediately adjacent the fold, said folded portion formed by the fastening projecting laterally and being adapted to engage the adjacent surface of the opposite end, and the extreme free end being straightened substantially into line with the main portion of the strap, and a slotted retaining member embracing said strap and engaging said folded portion. 60

5. In a strap fastener device of the character described, a strap having the end thereof folded twice back upon itself for a portion of its length and fastened together immediately adjacent the fold, said folded portion formed by the fastening comprising a three 70 ply portion projecting laterally and being adapted to engage the surface of the opposite end and the extreme free end being 75 straightened substantially into line with the main portion of the strap, and a slotted retaining member embracing said strap and engaging said folded portion.

6. In a strap fastener device of the character described, a strap having each of its ends folded back for a portion of their length and stitched immediately adjacent the folds, said folded portions formed by the stitching projecting laterally toward each 80 other, and a slotted retaining member embracing said straps and engaging one of said folded portions.

7. In a strap fastener device the combination of a strap having the end thereof folded 90 back upon itself for a portion of its length and stitched immediately adjacent the fold, said folded portion formed by the stitching projecting laterally and being adapted to frictionally engage the adjacent face of the 95 opposite end of the strap, and the extreme free end being straightened substantially into line with the main portion of the strap, and a rigid, slotted retaining member passing around the width of the strap, said slot being of a width adapted to receive not more 100 than twice the thickness of said strap.

In testimony whereof I affix my signature.

CLYDE S. NONNEMACHER.
